United States Patent Office

Des. 192,127
Patented Jan. 23, 1962

192,127

ROTARY DISTRIBUTOR FOR BAGGAGE OR THE LIKE

Herbert Sutcliffe Winfield, Port Hope, Ontario, Canada,
assignor to Mathews Conveyer Company, Ellwood
City, Pa., a corporation of Pennsylvania

Filed June 7, 1961, Ser. No. 65,502

Term of patent 14 years

(Cl. D55—1)

FIG. 1

FIGURE 1 is a perspective view of a rotary distributor for baggage or the like, and the broken lines indicating a chute are for illustrative purposes only;

I claim:

The ornamental design for a rotary distributor for baggage or the like, as shown and described.
